UNITED STATES PATENT OFFICE.

OLIVER P. MEGAHAN, OF WESTERVILLE, OHIO.

INSULATOR-SUPPORT.

Specification of Letters Patent.

Patented Jan. 5, 1915.

1,123,342.

Application filed November 15, 1913. Serial No. 801,299.

To all whom it may concern:

Be it known that I, OLIVER P. MEGAHAN, a citizen of the United States, residing at Westerville, in the county of Franklin and State of Ohio, have invented a certain new and useful Improvement in Insulator-Supports, of which the following is a specification.

When cross arms for electric conductors 10 are made entirely of cement they are costly to transport and are liable to breakage.

The object of the present invention is to provide an improved construction in which the body is made largely of cement but is 15 primarily made principally of sheet metal so that the cement can be applied to it at or near the place of use, thereby saving much of the cost of transportation and doing away altogether with the liability to breakage.

The invention consists in the general construction stated and also in certain details of construction hereinafter set forth in connection with the accompanying drawing, 25 which illustrates one embodiment of such invention.

In the said drawings—Figure 1 is an isometric perspective of somewhat more than one half of a cross arm according to 30 the invention. Fig. 2 is a longitudinal sectional view at one end of the cross arm showing details not shown in Fig. 1. Fig. 3 is a perspective like that shown in Fig. 1, but looking at the lower side of the arm. 35 Fig. 4 is a perspective view of a socket piece for the insulator holding pins. Fig. 5 is a detail section of the metallic shell on the line $\alpha-\alpha$ Fig. 1.

The metallic shell is cut and pressed out 40 of sheet metal to form a flat top 5, sloping sides 6, 6, curved upturned lips 7, 7, and a boss 8 having a vertical face at one or both sides to fit into the groove of the pole (not shown) on which the cross arm is to be secured. Formed with or attached to the shell 45 at each end is a metallic end piece 9 having a tongue 10. The structure thus described forms a sort of trough into which cement concrete 11 can be easily poured and tamped especially when in fluent form, but before 50 supplying the cement I locate U-shaped socket members 12 of metal each having a square hole 13 to receive a similarly formed

shoulder 14 on the metallic shank 15 of the glass or porcelain insulator-holder 16, such 55 an insulator being designed 17. The square socket prevents the insulator shank from turning and to prevent the withdrawal of the shank a nut 18 is threaded onto the shank where it projects above the cross arm. 60 The upper end of the shank is also threaded at 19 to receive a second insulator (not shown). The cement is worked somewhat into the channels formed by the curved lips 7, 7, and it engages those lips as well as the 65 tongue 10 binding all the parts together so that the metal of the shell cannot pull away from the cement or the cement from the shell. The middle boss is provided with a hole 20 for fastening the arm to a pole. 70 The shanks of the insulator holders can be secured in place at the time the concrete is supplied or the socket located and the shank holes formed by a suitable former and the shank of the insulator holders fitted in 75 afterward. The structure thus formed makes a durable cross arm with the cement portion thoroughly protected from the disintegrating effects of weather. The shells and shanks can be transported at small cost 80 to distant points, and the cement applied to the shells at the place of use.

What I claim is:

1. A cross arm for the pole of an electric conductor comprising, in combination, a 85 body of sheet metal formed as an inverted trough with inwardly and upwardly turned edges and with closing pieces for the ends of said body, said end closing pieces having notches engaged by said inwardly and upwardly turned edges, and a filling of cement concrete whereby the sides are locked from disengagement from the end pieces.

2. A cross arm for the pole of an electric conductor comprising, in combination, a 95 body of sheet metal formed as an inverted trough with inwardly and upwardly turned edges and with pieces closing the ends of said body, said end closing pieces having notches engaged by said inwardly and upwardly turned edges and tongues lying within the shell to be engaged by a cement filling, and the cement filling whereby the end piece is locked from movement in any direction, substantially as described.

3. A cross arm for the pole of an electric

105

conductor comprising, in combination, a body of sheet metal formed as an inverted trough with inwardly and upwardly turned edges, a closing piece for an end of said body connected with one of the walls of said body, said closing piece having notches engaged by said inwardly and upwardly

turned edges whereby the sides are locked from disengagement from said end, and a filling of concrete cement in said body.

OLIVER P. MEGAHAN.
